INVENTOR.

Martin Narodick,

Charles O. Sherry,
his ATTORNEY.

UNITED STATES PATENT OFFICE.

MARTIN NARODICK, OF CHICAGO, ILLINOIS.

GLARE-PREVENTING DEVICE FOR HEADLIGHTS.

1,333,033.

Specification of Letters Patent.

Patented Mar. 9, 1920.

Application filed May 8, 1919. Serial No. 295,680.

To all whom it may concern:

Be it known that I, MARTIN NARODICK, a citizen of the present Government of Russia, and a resident of Chicago, Cook county, 5 and State of Illinois, have invented certain new and useful Improvements in Glare-Preventing Devices for Headlights, of which the following is declared to be a full, clear, and exact description.

10 This invention relates to glare preventing devices for headlights and its principal object is to provide simple and efficient means which may be readily installed in headlights, and capable of minimizing the 15 "glare" which is commonly present in headlights, due to the presence of a parabolic reflector. This invention is particularly useful in connection with the headlights of automobiles and other motor vehicles, and 20 consists in a spirally arranged strip of material capable of being secured in the hollow space or cavity of the reflector of the headlight, and extending from the lens to and behind the source of light, which is 25 usually in the form of an incandescent electric light bulb. The invention further consists in the several novel features herein-after fully set forth and more particularly defined in the claims.

30 The invention is clearly shown in the drawing accompanying this specification, in which:

Figure 1 is a front elevation of a headlight, showing a simple embodiment of my 35 present invention applied thereto;

Fig. 2 is a face view of the device in its flat condition;

Fig. 3 is a vertical cross section of the headlight, taken on the line 3—3 of Fig. 1, 40 and showing the device therein in side elevation.

Referring to said drawing, the reference character 4 designates an automobile headlight of well-known construction, comprising the usual casing 5 in which is secured a parabolic reflector 6; a lens 7, and an annular or ring-like cover 8 removably secured to the casing 5 and arranged to hold the lens in place at the open front end of the reflector. 45 At the rear end of the reflector is secured an electric lamp socket 9 in which is removably secured an electric light bulb 10, as is well understood by those skilled in the art to which this invention pertains.

50 The glare preventing device is designated by the reference character 11 and in its sim-

plest form comprises a sheet of thin material such as aluminum, which is blanked out, by a suitable die, to form a substantially circular plate, as is illustrated in Fig. 2. Conveniently, a plurality of projections 12 are formed at the marginal edge of the circular plate which act as centering devices for the plate. Said plate is slit, by suitable dies, along the spiral lines 13, the slits commencing at the points 14 and terminating at the points 15, and leaving therebetween spiral shaped strips 16, 16^a. At the center of the plate is formed an opening 17 for the reception of the metal shell of the incandescent electric light bulb, and oppositely disposed notches 18 are formed at the edge of said opening 17 through which the usual pins or lugs on the shell of the incandescent light bulb may pass. Said pins or lugs 75 form the usual attaching means between the shell and socket of automobile headlights, as is well known.

The device is attached to the headlight by first removing the cover 8 with its lens 7, 80 and thereupon placing the glare preventing device against the usual gasket 19 which is held in a groove at the outer end of the reflector 6. The shell of the incandescent light bulb is then inserted through the 85 opening 17 and the bulb pushed back into the hollow of the reflector, and the shell inserted in the socket 9 and turned to bring the pins into the usual bayonet slots therein. The cover with the lens is then replaced, and 90 the marginal portion of the device is thereby clamped between the lens and gasket. It is to be observed that when the spiral strips are pushed backward, the convolutions thereof take the form of inclined spirals, 95 and conform substantially with the inner face of the reflector, and that reflected rays, which would normally be carried forward by the reflector, are intercepted by the convolutions of the glare preventer and only 100 those rays which pass laterally between the convolutions are projected out through the lens of the lamp. Consequently, the brilliant glare which is usually present in the headlights of automobiles, is prevented although the light issuing from the lamp is 105 bright and gives very satisfactory service for illuminating the road in front of the automobile. The device itself may have a polished surface, thereby acting in the 110 nature of a reflector.

More or less variation of the exact details

of construction is possible without departing from the spirit of this invention; I desire, therefore, not to limit myself to the exact form of the construction shown and 5 described, but intend, in the following claims, to point out all of the invention disclosed herein.

I claim as new, and desire to secure by Letters Patent:

10 1. As a new article of manufacture, a glare preventing device for headlights, comprising a spiral strip arranged to extend from the outer edge of the reflector of a headlight to a position behind the lamp of the head- 15 light, the several convolutions of the spiral strip acting to intercept the majority of light rays reflected by the reflector.

20 2. A glare preventing device for headlights, comprising a sheet of material having a spirally shaped slit formed therein to provide a spiral strip commencing adjacent the outer margin of the device and terminating adjacent its middle portion.

3. A glare preventing device for head-

lights, comprising a sheet of material formed 25 with a plurality of spiral slits which divide the sheet into a plurality of spiral strips which commence adjacent the outer margin 30 of the sheet of metal and terminate adjacent its middle portion.

4. A glare preventing device for headlights, comprising a sheet of material formed with a plurality of spiral slits which divide the sheet into a plurality of spiral strips 35 which commence adjacent the outer margin 35 of the sheet of metal and terminate adjacent its middle portion, there being a centrally located aperture, formed in said sheet of material, adapted to receive the shell of an incandescent light bulb.

5. A glare preventing device for headlights, comprising a sheet of material, having an outer annular flat portion and a spirally arranged strip extending in an inclined plane, from said flat portion to a 45 point along the axis of the device.

MARTIN NARODICK.
